CLAIM

The ornamental design for a firearm as shown and described.

DESCRIPTION

FIG. 1 is a partial isometric view of a first embodiment of a firearm, showing my new design;

FIG. 2 is a partial side view thereof;

FIG. 3 is partial top view thereof;

FIG. 4 is partial bottom view thereof;

FIG. 5 is a partial isometric view of a second embodiment of a firearm, showing my new design;

FIG. 6 is a partial side view thereof;

FIG. 7 is partial top view thereof;

FIG. 8 is partial bottom view thereof;

FIG. 9 is a partial isometric view of a third embodiment of a firearm, showing my new design;

FIG. 10 is a partial side view thereof;

FIG. 11 is partial top view thereof;

FIG. 12 is partial bottom view thereof;

FIG. 13 is a partial isometric view of a fourth embodiment of a firearm, showing my new design;

FIG. 14 is a partial side view thereof;

FIG. 15 is partial top view thereof; and,

FIG. 16 is partial bottom view thereof.

The dot-dash broken line represents a break line or, when adjacent to the claimed design, represents an unclaimed boundary of the claimed design. The broken lines depicting the remainder of the firearm show features that form no part of the claimed design.
